(57) **CLAIM**

The ornamental design for a sex toy assembly, as shown and described.

DESCRIPTION

FIG. 1 is a front, right, and top perspective view of the first part of a sex toy assembly, showing my new design; FIG. 2 is a rear, left, and bottom perspective view thereof; FIG. 3 is a front view thereof; FIG. 4 is a rear view thereof; FIG. 5 is a left side view thereof; FIG. 6 is a right side view thereof; FIG. 7 is an enlarged top plan view thereof; FIG. 8 is an enlarged bottom plan view thereof; FIG. 9 is a front, left, and top perspective view of the second part of the sex toy assembly; FIG. 10 is a rear, and left perspective view thereof; FIG. 11 is a front view thereof; FIG. 12 is a rear view thereof; FIG. 13 is a left side view thereof; FIG. 14 is a right side view thereof; FIG. 15 is an enlarged top plan view thereof; FIG. 16 is an enlarged bottom plan view thereof; FIG. 17 is a perspective view of the first part and the second part assembled together of the sex toy assembly; FIG. 18 is another perspective view of the first part and the second part assembled together of the sex toy assembly; FIG. 19 is a front, right, and top perspective view of the third part of the sex toy assembly; FIG. 20 is a rear and right perspective view thereof; FIG. 21 is a front view thereof; FIG. 22 is a rear view thereof; FIG. 23 is a left side view thereof; FIG. 24 is a right side view thereof; FIG. 25 is an enlarged top plan view thereof; FIG. 26 is an enlarged bottom plan view thereof; FIG. 27 is a perspective view of the first part and the third part assembled together of the sex toy assembly; FIG. 28 is another perspective view of the first part and the third part assembled together of the sex toy assembly; FIG. 29 is a front, right, and bottom perspective view of the fourth part of the sex toy assembly; FIG. 30 is a rear, and left perspective view thereof; FIG. 31 is a front view thereof; FIG. 32 is a rear view thereof; FIG. 33 is a left side view thereof; FIG. 34 is a right side view thereof;

(Continued)

FIG. 35 is an enlarged top plan view thereof;
FIG. 36 is an enlarged bottom plan view thereof;
FIG. 37 is a perspective view of the first part and the fourth part assembled together of the sex toy assembly;
FIG. 38 is another perspective view of the first part and the fourth part assembled together of the sex toy assembly; and,
FIG. 39 is a perspective view of the first part, second part, third part, and fourth part of the sex toy assembly shown separated.
The broken lines shown in the drawings illustrate portions of the sex toy assembly that form no part of the claimed design.
